DAVID G. DEE, OF ROCHESTER, NEW YORK, ASSIGNOR, BY MESNE ASSIGNMENTS, TO
ROCHESTER H. ROGERS, OF ROCHESTER, NEW YORK.

FIRE-ALARM TRUNK SWITCHING MECHANISM.

1,225,936.

Specification of Letters Patent. Patented May 15, 1917.

Application filed February 25, 1914. Serial No. 820,949.

To all whom it may concern:

Be it known that I, DAVID G. DEE, of Rochester, in the county of Monroe and State of New York, have invented certain new and useful Improvements in Fire-Alarm Trunk Switching Mechanisms; and I do hereby declare the following to be a full, clear, and exact description of the same, reference being had to the accompanying drawings, forming a part of this specification, and to the reference-numerals marked thereon.

My present invention relates to telephone fire alarm circuits and mechanisms whereby fire alarms or signals may be despatched from a telephone subscriber's substation to the central office or exchange and from there to the fire department headquarters, and it has for its object to provide a novel arrangement of apparatus whereby the use of one of several different alarm trunks leading to fire department headquarters will automatically distribute subsequent calls onto other trunks, thus preventing two or more operators from connecting two different circuits on which fire alarm calls may be received simultaneously at the central office, to one and the same trunk. To these and other ends the invention consists in certain improvements and combinations of parts, all as will be hereinafter more fully described, the novel features being pointed out in the claims at the end of the specification.

In the drawings:

The figure is a diagrammatic illustration showing the central office switchboard mechanism, subscribers' circuits and a plurality of trunks leading to fire department headquarters, together with the automatic switching devices controlling the distribution of calls over said trunks.

In practice, I have determined that for accuracy in operation and in order to avoid confusion it is desirable to have a plurality of trunk circuits leading from the central exchange or telephone office to the fire alarm headquarters, and I have also determined from the low percentage of the total number of fire alarm calls which are received within the same time interval that it is practically unnecessary to provide more than two of such trunks, the desirability of which is at once apparent from the sureness of operation of the apparatus and from the low cost of installation as compared with the expense

that would be incurred by unduly increasing the number of said trunks, and although my invention is not to be considered as limited in any way to a duplex trunking scheme, it will be understood that I prefer this circuit arrangement for the reasons previously given.

In the illustration I have shown two telephone subscribers' instrument circuits, comprising the line wires A, A' and B, B' provided with the usual telephone sets and equipped with alarm signaling mechanisms, such as a call box, indicated generally by revoluble notched wheels A², B² which open and close the pairs of contacts a and b in each of said circuits when the box mechanisms are set into operation. The subscribers' circuits terminate at the central office or telephone exchange in the usual terminals of the switchboard jacks A³, B³, each of which comprises the tip, ring and sleeve contacts a', a² and a³, and b', b² and b³. The tip and ring contacts are connected with the line wires of their respective subscribers' stations in the usual manner, as indicated by the wires a⁴, a⁵ and b⁴, b⁵. Associated with each of these circuits are the usual line relays, as indicated by a⁶ and b⁶, and cutoff relays a⁷, b⁷ which perform their usual functions. The main battery or source of current, indicated by X, is connected at its positive pole by the wires a⁸ and b⁸ which are connected respectively with the sleeve a³ of the jack A³ and the sleeve b³ of the jack B³, said sleeves being hereinafter referred to as the battery terminals.

The two out-going trunk circuits leading to the fire alarm headquarters comprise the pairs of wires F, F' and G, G' which lead to the two independent alarm and recording mechanisms F², G². These circuits are each supplied over one limb with current from the negative side of the main battery X, the other limbs being grounded through high resistance relays f, g, said grounds being indicated by f', g'. It will be understood that the battery X is grounded at its positive pole, as indicated at x. The trunks are, therefore, constantly supplied with current, but by reason of the high resistances interposed in the circuits the alarm and recording apparatuses being of low resistance are normally restrained from being operated, and, I am, therefore, enabled to combine with these circuits a testing apparatus, which is

normally inoperative, but which will be set into action to indicate an inoperative condition due to an opening of the trunk. Each of these relays f and g are provided with a normally open pair of contacts which, in respect to relay f are indicated by f^2 , f^3 in a local circuit consisting of the wires f^4 , f^5 , which include a buzzer, or other form of indicator f^6 and a battery x^2 . It will be seen that if the trunk circuit is open the high resistance relay f releases its contacts which close the local circuits and energizes the buzzer f^6 .

In order to guard the trunk circuits against grounding and to give an alarm in the event such a thing occurs, I also provide one of the limbs of each trunk with a relay coil f^7 , g^7 which normally maintain in open condition a pair of contacts f^8 , f^9 attached to the conductors f^4 , f^5 . The signals are despatched over the trunk circuits by the opening and closing of a pair of contacts in each indicated by F^3 and G^3 , the movement of which is controlled by the repeating relay F^4 , G^4 included in the central office apparatus.

The arrangement of the switchboard circuits or central office apparatus, which serves as a means of connection between the subscribers' circuits and one or another of the fire alarm trunks, and performs the switching operations, is associated with the cord circuits, two of which are arranged at each switchboard operator's section, and are generally designated as the "fire plugs". Two of these are shown in the drawing and indicated by C and D, but there may be any number of them depending upon the size of the switchboard, and which with the associated apparatus acts to perform their functions when a fire alarm signal is despatched over one of the trunks by the insertion of one of the fire plugs in one of the jacks, to automatically switch all of the other plug circuits onto the second trunk. Thus, it will be seen, that should it happen that two fire alarm signals are received by the same, or different, telephone operators it would be impossible to connect the respective subscribers' circuits with one and the same trunk.

In further describing the alarm trunk circuits it may be said that each of these include an electro-magnet F^4 , G^4 which for convenience will be termed the repeater since they repeat the impulses received from the signaling apparatus of the subscriber's line and cause corresponding impulses to be transmitted to the signal devices F^2 , G^2 . Both of these magnets are adapted to be energized by current received when one or the other of the plugs C and D are inserted in the line jacks, but the switching mechanism controls their circuits in such a manner that only one of them can be energized

at one time by the act of inserting a single plug. Further, when one magnet is energized and an alarm trunk is seized by the use of one plug the conjoint action of the switching relays causes the other magnet to be appropriated to and become capable of operation only by the second plug. Two of the strands of each plug are adapted to complete the subscriber's line circuit to one or the other of the repeater magnets F^4 , G^4 and by an arrangement of contacts on the switching relays C', D' normally closed branch circuits extend from each magnet to each plug and a normally open branch likewise extends from one of the magnets to both plugs. When a call is initiated by the insertion of a plug in a jack, the normally closed branch is opened and the seizure of the alarm trunk is caused by closing the open branch circuit. Since both of these open branch circuits control the one magnet (F^4) it therefore becomes the primary alarm trunk and will transmit the signals irrespective of which plug is used providing only one alarm is answered. The other or secondary alarm trunk will receive the second or subsequent call which may come in during the time the primary trunk is occupied and it is also immaterial as to which of the two plugs is used in answering the second call.

To this end there is associated with each cord circuit the switching relays C' and D', one terminal of each of said relays being connected by the wires c and d to the sleeve or battery contacts c' and d' of their respective cord plugs, the other terminals of said relays being tied to the negative side of the battery by the leads c^2 , d^2 connected with the common battery return wire X'. Relay C' controls a pair of normally closed contacts 1 and 2, and two pair of normally open contacts 3 and 4, and 5 and 6, the last mentioned contact spring being adapted when disengaged from spring 5 to engage spring 7. The corresponding contacts on D' are indicated by 10, 20, 30, 40, 50, 60 and 70.

The tip contact c^3 of the plug C is grounded over the wire c^4 and the ring contact c^5 is connected by the wire c^6 with a relay contact spring 6 which, when in engagement with spring 7 completes the circuit over the wire c^7 to one terminal of the repeating relay F^4 , the other terminal of said relay being connected to the battery lead X' by the wire c^8 . Associated with the switching relays C', D' are cutoff relays C², D², the former being provided with contacts 8 and 9, while the latter is provided with similar contacts 80 and 90. The contact 8 is connected with the wire c^2 by the tap e and the spring 9 is joined to the spring 2 by the wire e' , likewise the spring 1 is connected with the wire c by the lead e^2 . One termi-

nal of the coil C^2 is grounded by the wire e^3 , while the other terminal is connected by the wire e^4 with the contact spring 4, and the mate spring 3 is joined by the wire e^5 with the battery lead X' . In connection with this group of contacts it only remains to be said that the spring 4 is connected by the wire 44 with the contact spring 40 of the other set of relay contacts; the contacts 5 and 50 are tied together by the wire 55; and the contacts 7 and 70 are connected by the wires c^7 and 77. It will be noticed that one terminal of the coil of the cutoff relay D^2 is grounded over the wire d^{10} and the other end of the coil is connected to the contact spring 40 by the wire d^{11} , also that the contacts 20 and 90 are connected by the wire 29 and that the contact 80 is joined to the conductor d^2 by the wire d^{12} .

The repeating relay G^4 for the second trunk has one of its terminals connected to the wires 55 and 56, and its other extremity joined to the conductor d^2 by the wire 57, and at this point it will be noted that the wire d^2 is connected with the battery lead X' . Of the pairs of contacts G^3 of the second trunk one is connected to the ground g' which is also the terminal of one end of the coil g , and the other contact is connected to the other extremity of said coil g and to the wire G . The testing apparatus comprising the buzzer f^6 , previously described, may also be used for indicating the opposite condition of the second fire alarm trunk circuit, if desired, by providing the two pairs of normally open contacts g^2 , g^3 on the relay g , and g^8 , g^9 on the relay g^7 and connecting these by the wire g^{10} and g^{11} with the conductors of the circuit of the 40 buzzer or indicator f^6 .

Describing the operation of the apparatus *seriatim* it will be assumed first, to facilitate a clear understanding of the operation of the various relays and sets of contacts, that alarm signals are turned in or despatched from only one of the subscribers' stations omitting the complications which ensue when two fire alarm calls are received simultaneously. When a subscriber's alarm mechanism is operated the central office operator upon answering the call in the usual manner with the plug in an answering cord circuit, she receives a distinctive signal which informs her that the alarm mechanism is in operation and that the impulses of current despatched to the central office are not due to line disturbances. The means by which this distinctive signal is transmitted may be such as that forming the subject matter of Patent No. 1,008,313, granted November 14, 1911, to William L. Denio, or as shown in my pending application, Serial No. 711,471, for patent for fire alarm apparatus, filed July 25, 1912. As above stated, the central office

operator upon being informed of the despatch of a fire alarm signal over one or another of the subscribers' lines, connects that line directly with the trunk leading to the fire alarm headquarters by means of 70 one of the fire plug cord circuits, whereupon the impulses of current are transmitted to and repeated by one of the relays F^4 or G^4 and the blows indicating the number of the box are sounded by the gong and recording 75 devices F^2 , G^2 .

Upon the insertion of the plug C into the jack A^3 the following conditions are established: Ground is applied to one side of the subscriber's circuit; the switching relay C' is connected to the positive side of the battery and becoming energized shifts its contacts, and the repeating relay F^4 is connected to the subscriber's circuit, the contacts 6 and 7 being closed. The flow of current 80 through the switching relay C' may be traced over the following circuit: battery X , wire a^8 , cutoff relay a^7 , sleeve contacts a^3 , c' , wire c , coil C' , wire c^2 , resistance J , wire X' to battery. Similarly the circuit of the repeating 85 relay F^4 may be traced as follows: battery X , wires X' , c^8 , coil F^4 , wire c^7 , contacts 7, 6, wire c^6 , spring contacts c^5 , a^2 , wires a^5 , A , springs a , wires A' , a^4 , spring a' , tip c^3 , wire c^4 through ground to battery. The opening 90 and closing of the contacts a at the subscriber's station produce a corresponding movement of the normally open contacts F^3 of the first fire alarm trunk, which latter may be traced as follows: battery X , wire 95 X' , coil f^7 , conductor F' to the bell and recorder F^2 , thence over the wire F to the pair of contacts F^3 to ground f' , thence to the battery. Contact 3 is tied to one side 100 of the battery so that when it is closed into engagement with the spring 4 the circuit is completed from battery over wires X' , c^5 , contacts 3 and 4, wire e^4 , coil C^2 , wire e^3 to ground and the energizing of the last mentioned coil closes the normally open contacts 8 and 9, the effect of which is counteracted by the opening of the corresponding 105 normally closed contacts 1 and 2.

These conditions just described with respect to the switching relay C' and cutoff relay C^2 will be produced by the insertion of the plug C in any subscriber's line jack. Upon the insertion of the plug D in any of the jacks its corresponding switching relay D' and cutoff relay D^2 will be energized 115 and the alarm signal impulses repeated over the first trunk F , F' upon the opening and closing of the contacts F^3 on the repeating relay F^4 , providing, of course, the plug C is idle.

The switching of the fire plug cord circuits is such that in the event any one of a plurality, for example, ten cord circuits, is in use and one of the fire alarm trunk circuits is occupied, all of the other cord cir- 120 125 130

cuits, that is the remaining nine, are left on the other fire alarm trunk circuit, and it is, therefore, impossible to confound the operation of the signaling and indicating mechanism at fire department headquarters, as would otherwise result should it happen that two different switchboard operators both selected one fire alarm trunk at the same time. When the switching relay C' is energized in answer to the first incoming fire alarm call, the cutoff relay D² is also energized by current flowing over the following circuit: battery X, wires X', e⁵, spring contacts 3 and 4, wires 44, d¹¹, coil D², wire d¹⁰, to ground and thence to battery. The closing of the contacts 80 and 90 completes a shunt circuit around the coil of the switching relay D' which condition exists as long as the relay C' is energized, with the consequent result that, if during this time, the plug D is inserted in the jack D³ it can only effect the operation of the repeater G⁴ and despatch signals over the second fire alarm trunk G, G' as follows: The second fire alarm signal being received while the first signal is being transmitted, as previously described, and the plug D inserted in the jack D³ the battery circuit which is completed through the sleeve contacts b³ and d³ leads around the coil D' over the wire e²⁰, contacts 10 and 20, wire 29, contacts 90 and 80 and wire d¹². The contacts 50 and 60 thereupon remain in their normal condition and the complete circuit of the repeating relay may be described as follows: battery X, wires X', 57, coil G⁴, wires 56, 55, contacts 50 and 60, wire d⁶, rings d⁵, b², wires b⁵ and B', signaling contacts b, wires B, b⁴, tip spring b' and contact d³, wire d⁴ to ground and battery.

Reference heretofore to the first and second fire alarm trunk circuits necessarily presages the particular order of operation in respect to the two trunks F, F' and G, G', although either may be arranged to be the first to receive an incoming call, but in the arrangement shown if the plug D is inserted in the jack B³ while the plug C remains idle, the repeating relay F⁴ is seized and the following conditions established: The switching relay D' is energized by current flowing over the following circuit: battery X, wire b⁸, coil b⁷, sleeves b⁸, d³, wire d, coil D', wire d², resistance J, wire X' to battery. As a result of this contacts 10 and 20 are open, while the springs 30 and 40 are closed and 60 and 70 are brought together. When contact 30 engages spring 40 the former, which is connected to the wire X' by the lead 30⁸, connects battery to coil C², the complete circuit being traceable as follows: battery X, wires X', 30⁸, springs 30 and 40, wires 44, e⁴, coil C², wire e³ to ground and battery. The coil C² now closes its contacts 8 and 9 which completes the shunt circuit for the relay C', which circuit is indi-

cated by a wire e², contacts 1 and 2, wire e¹, contacts 8 and 9 and wire e, which latter is connected to the conductor c². The closing of the contacts 60 and 70 effects the selection of the first fire alarm trunk by the energizing of the repeater F⁴, the circuit of which will be seen to extend as follows: battery X, wires X', e⁸, coil F⁴, wire 77, contacts 70, 60, wire d⁶, ring contacts d⁵ and b², wires b⁵, B, contacts b, wires B', b⁴, tip spring b', contact d³, wire d⁴ to ground and battery.

It will now be seen that when the second incoming fire alarm call is received over the cord circuit C, the contacts of the switching relay C' remaining in their normal position, said call will traverse the following circuit: battery X, wires X', d², 57, coil G⁴, wires 56, 55, contacts 5 and 6, wire e⁶, ring contact e⁵, a², wires a⁵, A, contact a, wires A', a⁴, tip spring a' and contact e³, wire e⁴ to ground and battery. Coil G⁴, therefore, causes the contacts G³ to be closed and opened and the alarm impulses reproduced in the signal devices G².

I claim as my invention:

1. The combination with a plurality of telephone lines each provided with impulse despatching mechanism and terminating in line jacks at the central office, of a plurality of plugs each comprising a repeater trunk adapted to be connected with the telephone lines and having normally open contacts, relays for closing the latter adapted to be energized when the plugs are inserted in the jacks, of means for short circuiting the relay of one trunk when the other relay is operated.

2. In a telephone fire alarm trunk switching mechanism, the combination with two separate sets of signal apparatus, and a plurality of subscribers' telephone lines including telephone sets each line provided with means independent of said telephone sets for despatching impulses of current thereover, of central office switchboard mechanism for connecting the subscribers' lines with the signal apparatus comprising means co-operating with both sets of signal apparatus and serving to seize one set for the first incoming call and switch subsequent incoming calls onto the other set of signal apparatus.

3. In an alarm trunk signal switching mechanism for telephone fire alarm systems, the combination with a plurality of subscribers' lines, of separate sets of alarm mechanisms, an alarm signal despatching mechanism on each subscriber's line and operable independent of the normal functions of said line, a plurality of means for connecting the different lines and one or another of the alarm mechanisms upon the operation of a despatching mechanism, and apparatus associated with said connecting means for automatically appropriating one

of the alarm mechanisms to one of the subscribers' lines and rendering the other alarm mechanism capable only of being connected to another subscriber's line.

4. In an alarm trunk signal switching mechanism, the combination with a telephone exchange system comprising a plurality of subscribers' lines and a plurality of alarm trunks, of switch board plug circuits for connecting the subscribers' lines to the alarm trunks, and apparatus for connecting the plug circuits with one or another of the alarm trunks and serving when one trunk is connected to a line to connect the other plugs to the idle alarm trunk.

5. In a fire alarm telephone system, the combination with a plurality of subscribers' lines, a central exchange, a plurality of alarm trunks and a plurality of plug circuits for connecting said lines and trunks, of an automatically operated switching apparatus, controlling the connections between the plug circuits and trunks and acting to seize one trunk upon the connection of a plug to a line and to connect the remaining plugs to the other trunk.

6. The combination with a plurality of telephone subscribers' lines and a central exchange switch board having a plurality of operators' stations and a fire alarm plug circuit for each station connected in multiple and two impulse repeaters arranged to be controlled by the plug circuits, of separate alarm trunks governed by said repeaters, and switching devices controlling the seizure of one of the repeaters when a plug is connected to a line and also controlling the connection of the remaining plugs to the other repeater.

7. The combination with a plurality of telephone subscribers' lines and a central exchange switch board having a plurality of operators' stations and a fire alarm plug circuit for each station, two sets of alarm apparatus arranged to be operated by current impulses over one or another of the plug circuits, of switching devices controlling said plug circuits and acting when one of the latter is connected to a line to appropriate thereto one of the alarm apparatuses and to connect the other plug circuit to the second alarm apparatus.

8. In a telephone system, the combination with a switch board having line jacks, subscribers' lines terminating therein, said jacks having a third contact supplied with current, a plurality of alarm apparatus circuits having contacts and comprising alarm switch board plugs adapted to connect the alarm circuits to the subscribers' lines, a third contact on each plug adapted to cooperate with the third contact of the jacks, a relay controlling each alarm apparatus circuit and having circuits including the third contact of their respective plugs which

are energized when said plugs are inserted in jacks and means capable of operation by each relay for rendering all of the other relays inoperative.

9. In a fire alarm telephone system, the combination with a plurality of subscribers' circuits and two alarm apparatuses each comprising an electromagnet, of two alarm trunks each comprising two divisions one being a normally closed circuit connected to one magnet and the other a normally open circuit connected to the other magnet, a relay associated with each trunk and adapted to be energized when a trunk is connected to a line and acting to reverse the condition of the trunk contacts, means also controlled by each relay when energized for rendering the other relay inoperative.

10. In a trunk switching mechanism, the combination with an apparatus embodying two magnets, two trunks each having two branches including each of said magnets, one of said branches of each trunk being normally closed and the other being normally open, of a relay associated with each trunk and adapted when energized to reverse the condition of the branches of its respective trunk and means controlled by each relay when it is energized for rendering the other relay inoperative.

11. The combination with a telephone system comprising subscribers' circuits terminating in line jacks at a central office, said jacks also having a third contact supplied with battery, of an alarm apparatus comprising two magnets, trunks having plugs adapted to coöperate with the jacks and to connect them to the subscribers' circuits, each of said plugs also having a third terminal coöoperating with the battery contacts of the jacks, two branch circuits for each trunk connected to the magnets and contacts controlling the connections of the trunks with their respective branches, relays for operating the latter, each having a circuit connected to the third contact of a plug and adapted to be energized when the latter is inserted in a jack and other circuits also controlled by each relay when operated for rendering the other relay inoperative.

12. The combination with a plurality of subscribers' telephone lines terminating in line jacks at a central office, said jacks being also provided with a battery terminal, a plurality of plugs adapted to coöperate with said jacks each having two strands forming an alarm trunk adapted to be united with the subscribers' lines and a third conductor adapted to be joined to the battery terminal of a jack, of relays located in each of the third conductors and each adapted to be energized when its respective plug is inserted in a jack, alarm mechanisms comprising a plurality of electromagnets each having two circuits, one closed with and the

other adapted to be closed with the strands of one of the plugs and arranged to have their connections reversed by the energizing of their respective relays and means also controlled by the latter so that upon the energizing of one relay the other relays will be rendered inoperative.

13. In a telephone system, the combination with a plurality of subscribers' circuits, 10 a central office switch board apparatus comprising subscribers' line jacks and two alarm trunk cord circuit plugs and primary and secondary alarm mechanisms each comprising an electro-magnet, of a switching relay 15 for each cord circuit arranged to be energized when its respective plug is inserted in a jack, strands in the plugs adapted to form continuations of the subscribers' circuits, two normally open branch circuits 20 leading from the magnet of the primary alarm mechanism adapted to be connected to a subscriber's circuit by the action of either of the switching relays, other circuits leading from each of said magnets and normally 25 connected in circuit with the plug strands, and means for rendering either of said switching relays inoperative when the other has been energized.

14. The combination with a plurality of 30 primary circuits, of a plurality of secondary circuits, relays for establishing communication between any two of said circuits and means for making the remainder of said relays inoperative, to establish communication 35 between two other of said circuits.

15. The combination with a plurality of primary circuits, of a secondary circuit, relays for establishing communication between any one of said primary circuits with said 40 secondary circuit, and means for making the remainder of said relays inoperative during such communication.

16. The combination with a plurality of primary circuits, of a secondary circuit, 45 relays for establishing communication between any one of said primary circuits with said secondary circuit, associated relays adapted to be energized upon such communication being established, and means for making an idle one of said first relays simultaneously inoperative. 50

17. In a telephone fire alarm trunk switching mechanism, the combination with two sets of signal apparatus, and a plurality of subscribers' telephone lines, each including 55 a telephone set and an independent mechanism for despatching current impulses over said line, of central office switchboard mechanism for connecting the subscribers' lines with the signal apparatus, comprising 60 means coöperating with both sets of signal apparatus and serving to seize one set for the first incoming call despatched by an impulse mechanism aforesaid and switch subsequent incoming calls on to the other set of 65 signal apparatus.

18. In telephone fire alarm trunk switching mechanism, the combination with a switchboard, of subscribers' lines extending therefrom, and a plurality of trunks leading 70 to said switchboard, of a signal apparatus connected to each trunk, a signal despatching mechanism on each subscriber's line independent of the subscriber's telephone set, and means at the switchboard coöperating 75 with all of said trunks and serving to seize one trunk for the first incoming call from a signal despatching mechanism aforesaid and switch subsequent incoming calls on to the other trunks.
